UNITED STATES PATENT OFFICE.

HAROLD DE OLANETA, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

MANUFACTURE OF DRY CELLS.

Application filed May 7, 1920. Serial No. 379,514.

To all whom it may concern:

Be it known that I, HAROLD DE OLANETA, a citizen of the United States, residing in New Haven, New Haven County, Connecticut, have invented certain new and useful Improvements in the Manufacture of Dry Cells, of which the following is a full, clear, and exact description.

This invention relates to dry cells, and is particularly applicable to dry cells of the pocket or miniature type, such as commonly employed in connection with pocket flashlights, although the invention is not necessarily limited in this respect.

15 The present application is a continuation in part of my application, Serial No. 370,610 filed April 1st, 1920, and pertains more especially to the method of assembling a dry cell having one or more thin paper 20 washers surrounding the carbon electrode and surmounted by a pitch seal.

One of the primary objects of the invention is to provide a simple, convenient and economical method of assemblage of the 25 several parts of the cell.

Another object of the invention is to furnish an improved method of assembling the cell parts in cases where a centering device is used in the lower end of the zinc cup for 30 centering the depolarizing cartridge therein, there being an electrolytic paste interposed between the side surface of the cartridge and the inner surface of the side wall of the cup, and a paper washer at the top of the 35 cartridge beneath the pitch seal.

To these and other ends the invention consists in the novel features and steps and procedure to be hereinafter described and claimed.

40 In the accompanying drawing, Fig. 1 is a vertical central section of a flash-light dry cell, made in accordance with the invention, Fig. 2 is a section on a smaller scale, showing the first step in the operation, and Figs. 3 and 4 are sectional views showing later stages of the operation of assembling.

In Fig. 1 of the drawing, I have shown a 45 form of dry cell, in the assemblage of which my new method may be employed to advantage. The zinc cup 10, constituting one electrode, contains a carbon pencil 11, which serves as the other electrode, and such other electrode carries a depolarizing cartridge 12, consisting of suitable depolarizing material 50 tamped about the carbon and adhering to

the same. The cartridge is preferably contained within a porous envelope, such as a bag 13 of cheese cloth, or the like. Between the side surface of the cartridge and the inner surface of the side wall of the 60 zinc cup is a suitable electrolytic paste 14. In the bottom of the zinc cup is a centering disk 15 of paraffined paper, or the like, which centers the cartridge in the cup or receptacle. Overlying the cartridge 12 and 65 abutting the upper surface thereof is a washer 16 of paraffined paper, having an opening whereby it is fitted about the carbon electrode. Above the washer 16 is a washer 17, also of paraffined paper. The washer 17 70 is of cupped form, having a downwardly bulged central portion so as to provide a deep pocket near the center of the cell for the sealing material 18, and so as to provide also a peripheral chamber or space 19 75 for the accommodation of gas generated in the cell. The sealing material 18 consists of pitch, or the like, which, while in molten condition, is poured into the upper portion of the zinc cup on top of the upper paper 80 washer 17. The top of the carbon electrode is preferably provided with the usual brass contact cap 20.

85 The paste 14 is usually fairly stiff. In practice, it will contain, for example, a certain amount of wheat flour, or other cereal, and a chlorid solution; and by preference also, it contains a certain quantity of an amalgamating compound such as mercuric chlorid, for example. Preferably the paste 90 is cooked before being used, the flour, chlorid solution, and mercury compound being all mixed together with water and heated while the mass is being stirred.

95 In assembling the cell, a measured quantity of the paste is first placed in the bottom of the cup 10, so as to fill the same up to a certain level, as shown in Fig. 2. The carbon electrode 11, carrying the cartridge 12, has the centering disk 15 applied to the lower 100 end of the same and the two elements, that is to say, the cartridge and the bottom centering disk, are then dropped into the zinc cup so as to rest on top of the paste. The thin paper washer 16 is then placed on the 105 upper end of the projecting carbon pencil, which extends through the central opening in the washer. The cartridge is next forced into the paste to such extent that the paper washer 16 enters the mouth of the zinc cup 110

to a certain extent, as shown for example in Fig. 3. This operation may be performed manually, in a very convenient way, as it is merely necessary for the operative to place his or her finger on the upper end of the carbon pencil and give it a slight downward push. This is for the purpose of introducing the paper washer into the mouth of the zinc cup and in carrying out the operation the paste will be somewhat displaced, causing a portion of the same to flow along the side of the cartridge past the bottom centering washer to an extent such as indicated, for example, in Fig. 3.

15 The assemblage having been carried out manually to the extent indicated, it is next preferable, although not essential, to complete the operation of locating the cartridge in the zinc cup by subjecting the parts to pressure in a suitable machine, such as a light press. In the preferred practice the partially assembled cell is inverted and placed in a press having co-operating pressure members of the kind shown in Figs. 3 and 4. It has been found convenient to provide the press with a die bed 21, having a pedestal 22 of cylindrical shape, adapted to position the cartridge, and to equip the press with a plunger member 23, adapted to press down on the zinc cup while the cartridge member of the cell is fixedly held by the pedestal 22. The diameter of the upper cylindrical part of the pedestal 22 is approximately equal to the inner diameter of the zinc cup, so that it will fit nicely within said cup, and the upper portion of the pedestal 22 is also provided with a central cylindrical recess 24, adapted to receive the projecting end of the carbon pencil, preferably with a certain amount of clearance. It is desirable to subject the lower end of the cartridge to pressure, but to relieve the projecting end of the carbon pencil from any pressure or strain which might cause the same to break.

20 When the partially assembled cell has been placed in the press, as shown in Fig. 3, the upper end of the pedestal 22 will enter the mouth of the zinc cup to a slight extent, its upper face being in contact with the opposing face of the paper washer 16. The plunger 23 is then caused to make contact with the bottom of the inverted zinc cup and is moved downward from the position shown in Fig. 3 to that shown in Fig. 4. The downward movement of the plunger causes the paste to be flowed over the centering washer 15 downwardly into the space at the side of the cartridge; and the arrangement is such that the downward movement of the plunger 23 is arrested at the time that the paste is fully squeezed out of the upper part of the cup into the space at the side of the cartridge. The quantity of paste initially introduced into the cup is such that when the

upper end of the inverted zinc cup is brought against the centering washer 15, the side space within the zinc cup will be neatly filled by the paste without overflowing. In the operation of assembling, the lowermost portion of the paste strikes the upper surface of the paper washer 16, which serves as a stop for the paste and causes the same to be distributed laterally until, at the completion of the relative approaching movement between the members 22 and 23, the side surface of the cartridge is covered by a uniform layer of paste.

25 As the plunger 23 moves from the position shown in Fig. 3, to that shown in Fig. 4, the cup 10 is moved downwardly while being centered on the pedestal 22, the inner surface of the mouth portion of the cup sliding over the cylindrical surface of the pedestal. As previously stated, the lower end of the carbon pencil does not make contact with the pedestal, the recess 24 affording clearance in all directions. When the assembling is complete, the cell can be readily slipped off of the pedestal after the plunger has been raised.

30 After the operation just described, the cell is taken out of the press and the paper washer 17 is introduced into the upper end of the cup. The sealing material 18 is then poured into the zinc cup on top of the washer 17 and allowed to cool and set. The brass contact cap 20 is usually applied to the upper end of the carbon before the sealing material is poured in place.

35 It will be understood that I do not claim herein any features of the cell per se, and that I do not claim broadly herein the method of making a dry cell having a containing cup, a cartridge and a closure for the upper end portion of the cup, which comprises introducing a measured quantity of paste into the lower end of the cup and then squeezing the cartridge into the paste while the end closure is located against the upper end of the cartridge, whereby said end closure serves as a stop for the paste, as claimed in my application, Serial No. 370,610. Certain features in connection with the machine for assembling the cell are claimed in a co-pending application, Serial No. 382,471 no claim being made herein to the apparatus.

40 The member 22, which lies beneath the insulating washer 16, and with which the zinc cup makes contact in the assembling of the cell, is preferably made of hard rubber or like insulating material to prevent short circuiting.

45 What I claim is:

50 1. The method of making a dry cell having a containing cup, a cartridge, and a flexible washer positioned above the cartridge, which comprises introducing a measured quantity of paste into the bottom of the cup, then squeezing the cartridge into

the paste, and utilizing the flexible washer to arrest the displacement of the paste, by positioning such washer against the upper end of the cartridge while the squeezing operation takes place.

2. The method of making a dry cell, which comprises introducing a measured quantity of paste into the bottom of a zinc cup, then depositing in the cup, on top of the paste, a cartridge having an upwardly projecting electrode, placing a thin paper washer about the electrode on top of the cartridge, then placing the paper washer against a suitable abutment, and exerting pressure on the zinc cup to flow the paste into the space at the side of the cartridge, and relieving the projecting end of the carbon electrode from pressure, during displacement of the paste.

3. The method of making a dry cell, which comprises introducing a quantity of paste into the bottom of a containing cup; then introducing a cartridge into the paste, and then forcing the containing cup over a centering member independent of the cartridge.

4. The method of making a dry cell, which comprises introducing a quantity of paste into the bottom of a containing cup, then introducing a cartridge into the paste, and then forcing the containing cup over a centering member independent of the cartridge, which acts as an abutment to hold the cartridge stationary.

5. The method of making a dry cell, which comprises introducing a quantity of paste into the bottom of a zinc cup, then introducing a cartridge having an upwardly projecting electrode into the cup and then sliding the cup over a pedestal, which acts as an abutment for the cartridge, while relieving the projecting end of the electrode from pressure.

6. The method herein described, which comprises positioning a cartridge with a protruding pencil against a projecting centering member, placing a washer about the protruding portion of the pencil, and then sliding a containing cup over such centering member, while relieving the protruding end of the pencil from pressure during the movement of the cup.

7. The method of making a dry cell having a containing cup, a cartridge and a flexible washer positioned above the cartridge, which comprises introducing into the bottom of the cup the exact quantity of paste which is to be used in the cell and then squeezing the cartridge into the paste so that the latter flows into place at the side of

the cartridge, and arrests the outward movement of the paste.

8. The method of making a dry cell having a containing cup, a cartridge and a flexible washer above the cartridge, which comprises introducing into the bottom of the cup all the paste which is to be used in the cell, and then squeezing the cartridge into the paste while the washer is held in position relatively to the cartridge.

9. The method of making a dry cell having a containing cup, a cartridge and a flexible washer above the cartridge, which comprises introducing a measured quantity of paste into the bottom of the cup, and then squeezing the cartridge into the paste so that the latter is flowed along the side of the cartridge, until it reaches the washer and its movement is thereby arrested.

10. The method of making a dry cell having a containing cup, a cartridge having an upwardly projecting pencil and a flexible washer around the pencil above the cartridge, which comprises introducing a quantity of paste into the bottom of the cup, and then pressing the parts together while relieving the projecting end of the cartridge pencil from pressure.

11. The method of making a dry cell having a cup and a cartridge therein with an upwardly projecting pencil, which comprises positioning the cartridge against an abutment with the projecting end of the pencil free from contact with such abutment, placing a washer around the projecting end of the pencil and subjecting the cup and cartridge to pressure for bringing them into assembled relation.

12. The method of making a dry cell having a containing cup, a cartridge therein, with an upwardly projecting pencil, a centering disk in the cup beneath the cartridge and a flexible washer positioned about the pencil above the cartridge which comprises introducing into the bottom of the cup the total quantity of paste to be used in the cell, placing the centering disk and cartridge in the cup on top of the paste, placing the washer around the pencil, then subjecting the parts to pressure for displacing the paste from beneath the centering disk to a position alongside the cartridge, relieving the projecting end of the pencil from pressure during the pressing operation, and then suitably closing the upper end of the cell.

In witness whereof, I have hereunto set my hand on the 5th day of May, 1920.

HAROLD DE OLANETA.

1,564,951

Certificate of Correction.

It is hereby certified that in Letters Patent No. 1,564,951, granted December 8, 1925, upon the application of Harold de Olaneta, of New Haven, Connecticut, for an improvement in "The Manufacture of Dry Cells," errors appear in the printed specification requiring correction as follows: Page 3, lines 60 and 61, claim 7, strike out the comma and phrase ", and arrests the outward movement of the paste"; same page, line 69, claim 8, change the period after the word "cartridge" to a comma and insert the phrase *and arrests the outward movement of the paste*; and that the said Letters Patent should be read with these corrections therein that the same may conform to the record of the case in the Patent Office.

Signed and sealed this 19th day of January, A. D. 1926.

[SEAL.]

WM. A. KINNAN,
Acting Commissioner of Patent
